UNITED STATES PATENT OFFICE.

DAVID MCBAIN SYME, OF NEWPORT, RHODE ISLAND, ASSIGNOR TO HYDRO-CARBON BURNER MANUFACTURING COMPANY, OF NEWPORT, RHODE ISLAND, A CORPORATION OF RHODE ISLAND.

HYDROCARBON BURNER.

Application filed March 1, 1921. Serial No. 448,889.

To all whom it may concern:

Be it known that I, DAVID MCBAIN SYME, a citizen of the United States, and a resident of Newport, in the county of Newport and 5 State of Rhode Island, have invented a new and Improved Hydrocarbon Burner, of which the following is a full, clear, and exact description.

The invention relates to hydrocarbon 10 burners such as shown and described in the Letters Patent of the United States, No. 1,341,524, granted, May 25, 1920, to Karl A. Stahlgren.

The object of the present invention is to 15 provide a new and improved hydrocarbon burner arranged to produce a thorough atomizing of crude oil or other hydrocarbon fuel and to insure the formation of an intimate mixture of the atomized fuel and air 20 with a view to produce a practically complete combustion.

Another object is to spread the flame in 25 the combustion chamber to insure a uniform heating of the furnace or other apparatus to which the hydrocarbon burner is applied.

Another object is to permit of accurately regulating the inflow of the air to be mixed with the atomized fuel.

Another object is to provide a hydrocarbon 30 burner which is simple and durable in construction and arranged to readily withstand the high heat in the combustion chamber of the furnace.

With these and other objects in view the 35 invention consists of certain novel features of construction as hereinafter shown and described and then specifically pointed out in the claims.

A practical embodiment of the invention 40 is represented in the accompanying drawings forming a part of this specification, in which similar characters of reference indicate corresponding parts in all the views.

Figure 1 is a longitudinal central section 45 of the improved hydrocarbon burner with parts shown in elevation;

Figure 2 is a plan view of the same;

Figure 3 is a cross section of the same on the line 3—3 of Figure 1;

50 Figure 4 is a plan view of the cup-shaped atomizer;

Figure 5 is a front end view of the same; and

Figure 6 is a longitudinal central section of a modified form of the same.

Into the combustion chamber 10 of a furnace or other apparatus projects a revolute cup-shaped atomizer 11 provided at its rear end with a hub 12 journaled in a bearing 13 formed centrally on a spherical wall 14 of 60 an air inlet casing 15 attached to the front wall 16 of the furnace or other apparatus. The hub 12 of the cup-shaped atomizer 11 is secured on a hollow shaft 20 journaled in a bearing 21 attached to or formed on a bracket 65 22 preferably mounted on the air inlet casing 15. The shaft 20 is connected by a coupling 23 with the shaft 24 of an electric or other motor 25 of any approved construction and likewise mounted on the bracket 22. 70 It will be noticed that when the motor 25 is running a rotary motion is given to the cup-shaped atomizer 11.

Into the cup-shaped atomizer 11 discharges a liquid fuel supply pipe 30 extending through the hollow shafts 20 and 24 and connecting with a supply pipe 31 leading from a tank or other reservoir containing crude oil or other liquid fuel. The amount of liquid fuel passing to the pipe 30 is controlled by a suitable needle valve 32 arranged on a fixture 33 connecting the pipes 30 and 31 with each other.

The atomizer 11 is preferably made in the form of a cylindrical cup provided with a 85 conical recess 40 having its base end at the forward end of the cup, and into the rear apex end of this recess 40 discharges the liquid fuel supply pipe 30. The conical recess 40 has its wall 41 preferably in step 90 form, as shown in Figure 1, to insure a thorough breaking up or dividing of the liquid fuel into minute particles discharged into the combustion chamber from the front end of the recess, and owing to the conical 95 shape given to the recess 40 the atomized fuel is spread outward within the combustion chamber 10. The peripheral face of the atomizer 11 is preferably provided with a front and a rear set of impeller blades 42 100 and 43 set in staggered relation and with the rear blades 43 preferably set at a steeper angle. When the cup-shaped atomizer is started and liquid fuel passes into the recess 40 then this fuel is cut up by coming into contact with the steps of the recess wall, and this divided fuel is finally thrown out, by 105

centrifugal force at the front end of the cup-shaped atomizer, into the combustion chamber 10 in which it is ignited preferably by the use of a starting torch. In a very short time the heat from the burning fuel heats the cup-shaped atomizer 11 whereby the liquid fuel passing into the recess 40 by the supply pipe 30 becomes heated and vaporized and the vapors expand during their forward travel and are thrown by centrifugal force out of the cup into the combustion chamber to be burned therein as soon as it leaves the outer edge of the cup. The forward set of impeller blades produces a forwardly traveling current of air sufficiently strong to check the vapors as they leave the forward edge of the cup, and this current of air is caused by the impeller blades to travel with a helical thrust into the vapors to intimately commingle with the same and thus produce a flame of high heat and without producing smoke. The rear set of impeller blades sets up a current of air in the combustion chamber and this air also with helical thrust mixes with the vapors more remote from the edge of the cup to insure a complete combustion of the liquid fuel. It will also be noticed that the incoming air taken up by the impeller blades keeps the cup at practically a uniform temperature considerably lower than that in the combustion chamber thus preventing the cup from being burned, cracked or otherwise injured. As shown in Figure 6, the conical recess 40 of the cup-shaped atomizer 11 may be without the step wall 41.

The air inlet casing 15 is provided with an opening 50 in register with an opening 51 arranged in the front wall of the furnace or other apparatus on which the hydrocarbon burner is used, and the air inlet casing 15 is provided with an opening 50 in register with an opening 51 arranged in the front wall of the furnace or other apparatus on which the hydrocarbon burner is used, and the air inlet casing 15 is provided on its peripheral face with a series of openings 52 for the admission of air for ordinary draft use of the hydrocarbon burner. In case a forced draft is desired, use is made of a propeller 53 secured on the shaft 20 and extending within the spherical wall 14 of the air inlet casing 15. Openings 54 are formed in the wall 14 in front of the forced draft propeller 53 so that the air current induced by the latter passes through the openings 54, 50 and 51 into the combustion chamber 10.

In order to regulate the amount of air passing through the openings 54 use is made of a spherical valve or shutter 55 fitting onto the outer face of the wall 14 and having a hub 56 mounted to turn on the bearing 13. On the hub 56 is secured or formed a bevel gear wheel 57 in mesh with a pinion 58 se-

cured on a transverse shaft 59 journaled in suitable bearings on the casing 15. The outer end of the shaft 59 is provided with a handwheel 60 (see Figures 2 and 3) under the control of an operator for turning the shaft 59 with a view to rotate the valve or shutter 55 to admit more or less air through the openings 54.

In order to regulate the amount of air sucked or drawn in through the opening 52 of the air inlet casing, use is made of a shutter 70 mounted to slide on the peripheral face of the casing 15 and secured to two horizontally extending rods 71 mounted to slide in bearings 72 attached to or forming part of the bracket 22. The rods 71 are provided with racks 73 in mesh with segmental gear wheels 74 secured on a transversely extending shaft 75 journaled in brackets 76 (see Figure 3) attached to the casing 15. The shaft 75 is also journaled in a bearing 77 formed on the bracket 22 (see Figures 1 and 3). A handle 78 is attached to the shaft 75 to permit the operator to turn the shaft 75 with a view to cause the segmental gear wheels 74 to actuate the racks 73 and consequently the rods 71 whereby the shutter is moved forward or backward according to the direction in which the handle 78 is moved at the time. It is understood that this forward or backward movement given to the shutter 70 controls the amount of air passing through the inlet openings 52 in the peripheral face of the casing 15 for the purpose previously mentioned.

Having thus described my invention, I claim as new and desire to secure by Letters Patent:

1. In a hydrocarbon burner, an atomizer comprising a cup having a cylindrical periphery and interior means for atomizing and spreading the liquid fuel in front thereof, and propeller blades extending from the periphery for producing a current of air and projecting the same forward straight into the spread and atomized liquid fuel at an angle thereto.

2. In a hydrocarbon burner, an atomizer having a conical recess and having exterior air impelling means, the said recess having its side wall in step form, a liquid fuel supply means discharging into the said conical recess, and means for rotating the said atomizer.

3. In a hydrocarbon burner, a revoluble cup-shaped atomizer having a conical bore and exterior front and rear sets of impeller blades on the periphery of the same.

4. In a hydrocarbon burner, a revoluble cup-shaped atomizer having a conical recess and exterior front and rear sets of impeller blades arranged on the periphery of the atomizer, the blades arranged in staggered relation one to the other of the sets.

5. In a hydrocarbon burner, a revoluble cup-shaped atomizer having a conical recess and exterior front and rear sets of impeller blades, of which the rear set of 5 impeller blades is set to a steeper angle than that of the front impeller blades.
6. In a hydrocarbon burner, a revoluble cup-shaped atomizer having a conical recess into the rear apex end of which passes 10 the liquid fuel to be atomized, the said recess having a step wall and front and rear sets of impeller blades arranged on the peripheral surface of the atomizer.
7. In a hydrocarbon burner, a revoluble atomizer having a cylindrical periphery and a conical recess, the base of which is at the mouth of the atomizer to spread the atomized fuel in front of the atomizer, parallel series of impeller blades on the 20 exterior peripheral surface of the atomizer for producing a current of air and projecting the same into the said spread atomized fuel at an angle in front of the atomizer, and adjustable air admission 25 means for admitting air to the combustion chamber in which the hydrocarbon burner is located.
8. In a hydrocarbon burner, a revoluble atomizer having a conical recess, the base 30 of which is at the mouth of the atomizer to spread the atomized fuel in front of the combined nozzle and atomizer, a plurality of circular series of impeller blades on the exterior peripheral surface of the atomizer 35 for producing a current of air and projecting the same into the said spread atomized fuel in front of the atomizer, and a liquid fuel feed pipe arranged centrally in the said atomizer and discharging centrally 40 into the said conical recess at the apex end thereof.
9. In a hydrocarbon burner, a revoluble atomizer, having a conical recess, the base of which is at the mouth of the atomizer to spread the atomized fuel in front of the atomizer, impeller blades on the exterior peripheral surface of the atomizer for producing a current of air and projecting the same into the said spread atomized fuel in front of the atomizer, and a forced draft 50 propeller wheel independent of the impeller blades, rotating with the said atomizer at the rear thereof.
10. In a hydrocarbon burner, a revoluble atomizer having a conical recess, the 55 base of which is at the mouth of the atomizer to spread the atomized fuel in front of the atomizer, front and rear rows of impeller blades on the exterior peripheral surface of the atomizer for producing a 60 current of air and projecting the same into the said spread atomized fuel in front of the atomizer, a forced draft propeller wheel rotating with the said atomizer at the rear thereof, and forced air admission 65 means intermediate the said propeller and the atomizer.
11. In a hydrocarbon burner, a revoluble atomizer having a conical recess, the base of which is at the mouth of the atomizer to spread the atomized fuel in front of the atomizer, parallel rows of impeller blades on the exterior peripheral surface of the atomizer for producing a current of air and projecting the same into the said 70 spread atomized fuel in front of the atomizer, a forced draft propeller wheel rotating with the said atomizer at the rear thereof, forced air admission means intermediate the said propeller and the atomizer, 75 and manually controlled regulating means for the said forced air admission means to regulate the amount of air passing to the combustion chamber in which the hydrocarbon burner is located.

DAVID McBAIN SYME.
